UNITED STATES PATENT OFFICE.

WILLIAM DENNIS HUTCHINS, OF BLOOMBURG, TEXAS.

TRACK-FASTENER.

No. 893,504.

Specification of Letters Patent.

Patented July 14, 1908.

Application filed March 17, 1908. Serial No. 421,683.

To all whom it may concern:

Be it known that I, WILLIAM D. HUTCHINS, a citizen of the United States, residing at Bloomburg, in the county of Cass and 5 State of Texas, have invented certain new and useful Improvements in Track-Fasteners; and I do hereby declare the following to be a full, clear, and exact description of the invention, such as will enable others skilled 10 in the art to which it appertains to make and use the same.

This invention relates to new and useful improvements in metallic track fasteners and has for an object to provide a novel device of 15 this character which will effectually hold the rails to the supporting ties.

It is also an object of the invention to provide a novel device of this character which may be employed to produce a joint for the 20 meeting ends of rails.

It is a further object of the invention to provide a novel device of this character which will be simple in construction, effective in practice and economical to manufacture.

25 With the above and other objects in view the invention consists of the details of construction and in the novel arrangement and combination of parts to be hereinafter referred to.

30 In describing the invention in detail reference will be had to the accompanying drawings forming a part of this specification, wherein like characters of reference denote corresponding parts in the several views, and 35 in which,

Figure 1 is a view in top plan of a track-way showing the invention applied. Fig. 2 is a longitudinal sectional view through one of the ties illustrating the means employed 40 in effecting a rail joint. Fig. 3 is a view in perspective, detached, of the track fastener employed in conjunction with the joint. Fig. 4 is a view in perspective of an end of a tie employed in conjunction with the joint.

45 In the drawings 1 denotes ties of ordinary construction and 2 the ties employed in effecting a joint of the meeting ends of rails, said ties being positioned adjacent said meeting ends as is shown in Fig. 1.

50 The ordinary clamping-plates are of a structure similar to the fish plates commonly known excepting that each plate has a centrally projecting portion 3 of approximately

the same width as the supporting tie through which passes a vertically arranged bolt 4, 55 said bolt also passing through the tie. This bolt is inserted through the tie with the head therebeneath so that the threaded portion of the bolt will be exposed in order to expedite the application of the nut 5. The portions 60 of the plate adjacent the extension 3 are provided with down turned flanges 6 which snugly or tightly bear against the base of the rail. It might be also well to state that the base of the rails is seated within transverse 65 recesses or pockets formed in the upper surfaces of the tie as is well known.

When the fastener is employed for effecting a joint it is of such length as to rest upon both of the ties 2. Adjacent the meeting 70 ends of the rails the fastener is provided with the perforated web engaging portion 7 having openings 8 therein for the passage of the usual clamping bolts. The base portion 9 of the fastener is provided with spaced extensions 10 adapted to rest on each of the ties 2. The member is further provided between the extensions 10 with a flange 11 and on its outer portion with a flange 12. These flanges 11 and 12 are adapted to engage with the base 80 of the rail as has been hereinbefore referred to with reference to the clamp fasteners 3.

The extensions 10 are provided with perforations 13 through which pass the upper or threaded ends of the bolts 14. These bolts 85 14 also pass through elongated plates 15 and the ties 2. The plates 15 are positioned within longitudinal grooves 16 having their ends in communication with the transverse pockets 17 in which the bases of the 90 rails rest. The outer edge of each of the pockets 17 is provided with an apron 18 to engage the upper surface of the base of the rail, while the opposite edge 19 is straight or vertical. This is done to permit the ready 95 insertion of the base of the rail within the pockets. The plate 15 affords the opposite clamp and has its ends recessed as at 20 to engage the inner flange of the base as is fully shown in the sectional Fig. 2.

100 What I claim is:

In combination with the meeting ends of rails, supporting ties therefor having transverse pockets in which the bases of the rails rest, and having a longitudinal groove communicating with the pockets, and a plate 105

resting within the groove and engaging the inner flanges of the rails, and track fasteners arranged on opposite sides of the rails, each of said fasteners having extensions resting on the ties, and securing means passing through the ties and the extensions, certain of the fastening means passing through the plate.

In testimony whereof I have signed my name to this specification in the presence of two subscribing witnesses.

WILLIAM DENNIS HUTCHINS.
